UNITED STATES PATENT OFFICE.

THOMAS J. LINNEKIN, OF NEW YORK, N. Y., ASSIGNOR TO DREYFUSS & SACHS, OF SAME PLACE.

DESIGN FOR CARD-BASKET.

Specification forming part of Design No. **11,296**, dated July 15, 1879; application filed May 2, 1879.
[Term of patent 3½ years.]

To all whom it may concern:

Be it known that I, THOMAS J. LINNEKIN, of the city, county, and State of New York, have originated and designed a Card Basket or Receptacle, of which the following is a full, clear, and exact description, reference being had to the accompanying drawing, making part of this specification.

A represents the receptacle for cards. Its design is that of a four-sided figure, each one of the sides *a* being curved and recurved at *b*, *c*, and *d*, the four sides converging at *e*, at which point is suspended an ornamental pendant, *B*. Each of the four corners *f* of the receptacle also is ornamented by pendent balls *g*, and the edges *h* are trimmed with chenille or other ornamental covering.

Above the receptacle *A*, and supported by four columns, *C*, is an ornamental top, *D*,

curved as at *k*, and coming to a point, *l*, at the top. The edges *m* of this top are covered by chenille or other ornamental covering, and the four sides of the top are ornamented with worsted-work, as at *n*. From the four corners *o* of the top are suspended tassels or balls *p*, and likewise from these corners extend cords *r*, by which the basket is suspended. The entire design represents a suspended pagoda.

What I claim as my invention is—

A design for a card-basket, consisting of a top, *D*, with curves *k*, columns *C*, and receptacle *A*, formed with sides curved as at *b c d*, substantially as described and shown.

THOMAS J. LINNEKIN.
